Application October 28, 1957, Serial No. 692,849

Claims priority, application Germany October 26, 1956

14 Claims. (Cl. 123—32)

The present invention relates to a fuel injection arrangement.

More particularly, the present invention relates to a fuel injection arrangement for an internal combustion engine of the type wherein an electrically operated valve is used to control the flow of fuel to the engine. In known arrangements of this type the valve is a normally closed one and is opened upon energization, and such energization is brought about automatically by a switch device which is synchronized with the operation of the engine. In such arrangements there arises the problem of providing suitable means for controlling the duration of fuel injection, i.e., of providing suitable means for maintaining the valve open the required length of time depending upon the conditions under which the engine is operated, such as high speed, low speed, full load, partial load, etc. Experience has shown that considerable difficulties arose in converting the various required time lengths into electrical quantities which control the operation of the valve that regulates the fuel supply to the engine.

It is therefore an object of the present invention to provide a fuel injection arrangement which overcomes the above disadvantages.

It is another object of the present invention to provide a fuel injection arrangement in which the time interval during which fuel is injected is easily controlled.

It is yet another object of the present invention to provide a fuel injection arrangement wherein the time interval during which fuel is injected is predetermined independently of the instant at which fuel injection commences.

The objects of the present invention also include the provision of a fuel injection arrangement which may be constructed and maintained at very low cost, and which will give long periods of trouble-free service.

The objects of the present invention additionally include the provision of a fuel injection arrangement which may readily be built into existing constructions.

With the above objects in view, the present invention mainly consists in a fuel injection arrangement for an internal combustion engine which comprises valve means for controlling the flow of fuel to the engine and means which are operatively associated with the engine and with the valve means for opening the latter at a predetermined instant during a cycle of operation of the engine and for closing the valve means after the elapse of a time interval the duration of which is predetermined independently of the instant at which the valve means are opened.

More particularly, the present invention comprises electrically operated valve means for controlling the flow of fuel to the engine, the construction of the valve means being such that when it is unenergized it occupies its closed position and that when it is energized it occupies its open position; a source of electrical energy; an electron flow control device having a control branch and a power branch through which electrons may flow only when the control branch is electrically biased above a pre-

2

terminated minimum voltage, the power branch being in circuit with the source of electrical energy and with the valve means; voltage supplying means for impressing across the control branch at a predetermined instant during a cycle of operation of the engine a voltage greater than the minimum voltage, the voltage supplying means being so constructed and arranged that the duration of the impression of voltage is shorter than the time interval throughout which the valve means is to be maintained in its open position; and a resistor-capacitor time delay circuit connected across the control branch and adapted to be charged by the voltage supplying means during the impression of voltage across the control branch to a voltage greater than the minimum voltage for maintaining the voltage across the control branch above the minimum voltage for a predetermined time interval following the cessation of the impression of voltage by the voltage supplying means.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a schematic diagram of a fuel injection arrangement according to the present invention; and

Fig. 2 is a voltage-time graph illustrating the operation of the circuit shown in Fig. 1.

Referring now to the drawings, and to Fig. 1 thereof in particular, there is shown a fuel injection arrangement which incorporates an electrically operated valve V. The latter controls the flow of fuel from a supply conduit L to a connecting conduit O which communicates with the internal combustion engine (not shown). The valve is of the electro-magnetic type and includes a winding M which attracts a valve plunger P. The latter is continuously urged downwardly, as viewed in Fig. 1, to its closed position by a suitable bias spring (not shown), but is raised to its open position upon energization of the coil M. Thus, the valve V is one which when unenergized occupies its closed position and when energized occupies its open position.

The winding M is connected in circuit with the collector K and the emitter E of a transistor T, as well as with a source of electrical energy G, the latter normally being the battery or other D.C. source which is usually associated with an internal combustion engine. The base of the transistor is indicated at B, the connection of the transistor being of the common-emitter type so that the collector-emitter circuit constitutes the power branch of the transistor and the base emitter the control branch. As is well known in the art, the transistor is an electron flow control device which is conductive only when a certain minimum electrical bias is impressed across the control branch. This means that electrons may flow through the power branch of the transistor only when a voltage greater than the required minimum voltage is impressed across the control branch. In practice, the transistor may be a 2 N 173.

The base B of the transistor T is connected to the source of electrical energy G by way of a time delay switch D and an additional switch S. The latter has a stationary contact b and a movable contact a which can be moved to closed position by a rotating cam N which is suitably coupled to the crankshaft of the engine (not shown) so that the switch S is periodically actuated by and operates in synchronism with the engine. In this way, the switch S will, during successive cycles of operation of the engine, always be closed at the same pre-

determined instant, which, in practice, is the instant at which the work stroke commences.

The time delay switch D has a stationary contact *d* and a normally closed movable contact arm *e* which is mechanically connected to an armature that cooperates with a winding W. The electrical connection of the latter is such that when the switch S is closed, the winding is energized by the source G and the switch D opened. The switch D is so constructed and arranged that there is a brief delay between the instant the winding W is energized and the instant that the arm *e* is actually moved out of engagement with the stationary contact *d*. This time delay, the significance of which will be described below, is of the order of several milliseconds.

Additionally, a resistor-capacitor time delay circuit Z is connected across the control branch of the transistor, i.e., across the base B and the emitter E. The time delay circuit includes a capacitor C, a variable charging resistor R₁, and a variable discharge resistor R₂.

The operation of the above-described fuel injection arrangement is as follows:

The cam N closes the switch at the start of the work stroke of the engine. As a result, the control branch of the transistor T, the time delay circuit Z, and the winding W of the time delay switch D are connected across the source G, and this causes the following:

(1) With the voltage of the source G being greater than the minimum voltage required to render the transistor conductive, a sufficiently high voltage is impressed across the control branch to render the transistor conductive (the transistor having been left non-conductive at the end of the previous cycle of operation). This, in turn, permits a current to flow through the power branch so that the winding M of the valve V is energized, thereby raising the plunger P and opening the valve V. It will be apparent that the valve V will be maintained in its open position only so long as the electrical bias across the control branch of the transistor is sufficient to permit enough current to flow through the power branch as will adequately energize the winding M. For purposes of explanation, it will be assumed that the winding M is sufficiently energized to hold the plunger P in its open position so long as the transistor T is conductive.

(2) A charging voltage is applied to the capacitor C of the time delay circuit Z.

(3) The winding W of the time delay switch D is energized.

The above-described three events occur simultaneously. As set forth above, there is a brief time delay between the instant of energization of the winding W and the actual opening of the switch S, and the capacitance of the capacitor C and the resistances of the resistors R₁ and R₂ are such that the time delay is sufficient for the capacitor C to be charged to a voltage which is higher than the minimum voltage required to maintain the transistor T in conductive state. Consequently, by the time the contact arm *e* of the switch D is actually moved out of engagement with the stationary contact *d*, the voltage U_c across the capacitor C which, upon opening of the switch D, is the voltage U_b impressed across the control branch of the transistor, will be sufficient to maintain the transistor conductive so that current will continue to flow through the power branch thereby maintaining the valve V in its open position.

As soon as the switch D is opened, the capacitor C will commence to discharge by way of a parallel circuit one branch of which is constituted by the resistor R₂ and the other branch of which is constituted by the series circuit formed by the resistor R₁ and the emitter-to-base resistance of the transistor (the resistor R₃ being of no consequence). As soon as the capacitor has discharged to a point at which U_c is less than the voltage required to render the transistor conductive, no further current can flow through the winding M and the valve V assumes its closed position. Thus, the valve will have remained

open for a certain predetermined interval following the initial closing of the switch S, it being apparent that the length of this interval can be regulated by varying the resistances of the resistors R₁ and/or R₂.

Fig. 2 is a graphical representation of the voltage-time relationships between the various circuit components, it being assumed that the effect of the resistor R₃ is negligible.

The solid horizontal line t_S represents the time during which the switch S is closed, and it will be seen that the initial closure of this switch occurs at the instant t₁, the exact time at which the switch thereafter opens under the influence of the cam N being of no particular interest, suffice it to say that the switch remains closed throughout a fraction of each cycle of operation but for a period not less than the brief time interval required for the switch D to open after energization of the winding W.

The time during which the switch D is closed is represented by the solid horizontal line t_D. This switch—

which will, during the previous cycle, have assumed its closed position as soon as the cam N permits the switch S to open—is still closed at the instant t₁, and will not, due to its inherent time delay indicated by the bracket t_L, open until the instant t₂. In practice, the time delay will be approximately 5 milliseconds, and during this time interval t_L the voltage U_b, i.e., the voltage impressed across the control branch of the transistor, is equal to the voltage U_g which is the voltage of the source G and is of the order of 12 volts. Also, during this time interval t_L the capacitor C will be charged by the source G, and the voltage U_c across the capacitor will increase substantially linearly, as indicated by the dotted line τ_1 . With the capacitance of the capacitor C being 100 microfarads and the resistance of the resistor R₁ being 50 ohms, the resistor-capacitor circuit R₁, C has a charging time constant of 5 milliseconds and the capacitor will, during the time interval t_L, be charged to a voltage U₁.

Upon opening of the time delay switch D at the instant t₂, the control branch of the transistor as well as the time delay circuit Z are disconnected from the source G, and the only voltage which appears across the control branch is the voltage U_c across the capacitor. Of course, this voltage immediately begins to drop since the capacitor C commences to discharge by way of the resistor R₂ as well as by way of a parallel branch constituted by the resistor R₁ and the emitter-to-base resistance of the transistor (the resistance of the resistor R₃ being considered negligible). With the resistance of resistor R₂ being about 150 ohms, the discharge time constant is about 10 milliseconds, this time constant being indicated by the line τ_2 .

As soon as the voltage U_c, which is the same as the voltage U_b appearing across the control branch of the transistor, drops to the voltage U₀ at which the transistor ceases to be conductive, no more current will flow through the power branch. This occurs at the instant shown at t₃, at which time the valve V assumes its closed position. Thus, the total time during which the valve V is open is the time interval indicated by the bracket t_v.

The time interval during which the valve remains open may be increased by decreasing the resistance of resistor R₁. This decreases the charging time constant as indicated by the line τ_{11} the slope of which is steeper than that of line τ_1 . Inasmuch as the charging time of the capacitor remains constant, this factor being determined solely by the inherent time delay of the time delay switch D, the voltage to which the capacitor will be charged is increased so that at the instant t₂ the voltage U_c is equal to U₂ which is higher than U₁.

With the discharge time constant τ_2 remaining unchanged, the voltage U_b will not drop to U₀ until t₄, so that the valve V is retained in its open position for a period of time longer than before.

Additionally or alternatively, the time interval during which the valve remains open may be increased by in-

creasing the resistance of the resistor R_2 . This increases the discharge time constant as indicated by line τ_2 , so that the voltage U_b will not drop to U_0 until t_5 .

Thus, the time interval throughout which the valve V remains open subsequent to the closing of the switch S, and consequently the amount of fuel supplied into the engine, may be regulated within very wide limits independently of the instant at which fuel injection commences.

According to the present invention the time regulation may be accomplished automatically by providing a device for periodically short-circuiting the capacitor C, or for periodically connecting an additional resistor R_4 across the capacitor, thereby decreasing the discharge time thereof. Such a device includes a periodically-actuated switch Q which is also operated in synchronism with the engine and which may, if desired, be operated at a frequency which is a multiple of the frequency at which the switch S is operated. Thus, the discharge time of the capacitor, and consequently the time interval during which the valve V is kept open following the initial closing of the switch S during each cycle, may be regulated within wide ranges partly by varying the resistance of the resistor R_4 but mainly by selecting the particular instants of opening and closing of the switch Q.

It is also within the scope of the present invention to provide a fuel injection arrangement wherein the charging time of the capacitor is controlled by an element other than an electromagnetic time delay switch. For example, a toggle switch which is continuously biased into one position and a second transistor may be used. It is also possible to control the voltage to which the capacitor is charged by using as the source of electric energy G a generator which is coupled to the engine so that the output of the generator increases upon increased rotational speed.

It will be understood that each of the elements described above, or two or more together, may also find a useful application in other types of control arrangements differing from the types described above.

While the invention has been illustrated and described as embodied in a fuel injector arrangement for an internal combustion engine, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a fuel injection arrangement for an internal combustion engine, in combination, electrically operated valve means for controlling the flow of fuel to the internal combustion engine, said valve means when unenergized occupying its closed position and when energized occupying its open position; a source of electrical energy; an electron flow control device having a control branch and a power branch through which electrons may flow only when said control branch is electrically biased above a predetermined minimum bias, said power branch being in circuit with said source of electrical energy and with said valve means; biasing means for impressing across said control branch at a predetermined instant during a cycle of operation of the engine a bias greater than said minimum bias, said biasing means being so constructed and arranged that the duration of the impression of bias is shorter than the time interval throughout which said valve means is to be maintained in its open position; and a resistor-capacitor time delay circuit connected across

said control branch and adapted to be charged by said biasing means during the impression of bias across said control branch to a bias greater than said minimum bias for maintaining the bias across said control branch above said minimum bias for a predetermined time interval following the cessation of the impression of bias by said biasing means.

2. In a fuel injection arrangement for an internal combustion engine, in combination, electrically operated valve means for controlling the flow of fuel to the internal combustion engine, said valve means when unenergized occupying its closed position and when energized occupying its open position; a source of electrical energy; an electron flow control device having a control branch and a power branch through which electrons may flow only when said control branch is electrically biased above a predetermined minimum voltage, said power branch being in circuit with said source of electrical energy and with said valve means; a resistor-capacitor time delay circuit connected across said control branch; and means connected in parallel with said control branch and with said time delay circuit for impressing thereacross at a predetermined instant during a cycle of operation of the engine a voltage which is greater than said minimum voltage, said last-mentioned means being so constructed and arranged that the duration of the impression of voltage is shorter than the time interval throughout which said valve means is to be maintained in its open position, whereby said time delay circuit is charged to a voltage higher than said minimum voltage and maintains the voltage across said control branch above said minimum voltage for a predetermined time interval following the cessation of the charging of said time delay circuit.

3. In a fuel injection arrangement for an internal combustion engine, in combination, electrically operated valve means for controlling the flow of fuel to the internal combustion engine, said valve means when unenergized occupying its closed position and when energized occupying its open position; a source of electrical energy; a transistor having a control branch and a power branch, the latter being in circuit with said source of electrical energy and with said valve means; voltage supplying means operatively associated with the engine and in circuit with said control branch of said transistor for impressing thereacross at a predetermined instant during a cycle of operation of the engine a voltage greater than that which is required to render said transistor conductive; and a resistor-capacitor time delay circuit connected across said control branch of said transistor and adapted to be charged by said voltage supplying means, while the latter impresses a voltage across said control branch, to a voltage greater than said voltage which is required to render said transistor conductive, whereby said transistor remains conductive for a predetermined time interval following the cessation of the impression of voltage by said voltage supplying means.

4. In a fuel injection arrangement for an internal combustion engine, in combination, electrically operated valve means for controlling the flow of fuel to the internal combustion engine, said valve means when unenergized occupying its closed position and when energized occupying its open position; a source of electrical energy; a transistor having a control branch and a power branch, the latter being in circuit with said source of electrical energy and with said valve means; voltage supplying means operatively associated with the engine and in circuit with said control branch of said transistor for impressing thereacross at a predetermined instant during a cycle of operation of the engine, a voltage greater than that which is required to render said transistor conductive, said voltage supplying means being so constructed and arranged that the duration of the impression of voltage is shorter than the time interval throughout which, in said cycle, said valve means is to be

maintained in its open position; and a resistor-capacitor time delay circuit connected across said control branch of said transistor and adapted to be charged by said voltage supplying means, while the latter impresses a voltage across said control branch, to a voltage greater than said voltage which is required to render said transistor conductive, whereby said transistor remains conductive for a predetermined time interval following the cessation of the impression of voltage by said voltage supplying means and said valve means is maintained in its open position until the charge on said time delay circuit has dropped to a value at which the voltage across said control branch is below said voltage which is required to render said transistor conductive.

5. The combination defined in claim 4 wherein said time delay circuit includes a resistor and a capacitor in series-circuit connection.

6. The combination defined in claim 4 wherein said time delay circuit includes a resistor and a capacitor in parallel-circuit connection.

7. The combination defined in claim 4 wherein said time delay circuit includes a capacitor, a first resistor in series-circuit connection with said capacitor, and a second resistor in parallel-circuit connection with said capacitor.

8. The combination defined in claim 6 wherein said resistors are variable resistors.

9. The combination defined in claim 4 wherein said time delay circuit includes means connected across the capacitor for periodically short-circuiting the same, whereby the discharge time of said time delay means, and consequently the time interval during which said valve means is maintained in its open position, is diminished.

10. The combination defined in claim 4 wherein said time delay circuit includes means connected across the capacitor for periodically connecting an additional resistor thereacross, whereby the discharge time of said time delay means, and consequently the time interval during which said valve means is maintained in its open position, is diminished.

11. The combination defined in claim 3 wherein said voltage supplying means include a time delay switch connected in circuit with the parallel circuit constituted by said control branch of said transistor and said resistor-capacitor time delay circuit, said time delay switch being normally closed and having an electrically energizable actuator, said time delay switch being so constructed and arranged that when said actuator thereof is energized, said switch assumes its open position a predetermined time interval thereof, said voltage supplying means further including an additional switch which is connected in circuit with the series-parallel circuit constituted by said control branch of said transistor, said time delay circuit and said time delay switch and which is also connected in circuit with said actuator of said time delay switch for electrically connecting said series-parallel circuit as well as said actuator of said time delay switch, at said predetermined instant during a cycle of operation of the engine, to a source of electrical energy, whereby said

series-parallel circuit is electrically connected to the source of electrical energy for the duration of said predetermined time interval of said time delay switch.

12. The combination defined in claim 3 wherein said voltage supplying means include a time delay switch connected in circuit with the parallel circuit constituted by said control branch of said transistor and said resistor-capacitor time delay circuit, said time delay switch being normally closed and having an electrically energizable actuator, said time delay switch being so constructed and arranged that when said actuator thereof is energized, said switch assumes its open position a predetermined time interval thereof, said voltage supplying means further including an additional switch which is connected in circuit with the series-parallel circuit constituted by said control branch of said transistor, said time delay circuit and said time delay switch and which is also connected in circuit with said actuator of said time delay switch for electrically connecting said series-parallel circuit as well as said actuator of said time delay switch, at said predetermined instant during a cycle of operation of the engine, to said source of electrical energy, whereby said series-parallel circuit is electrically connected to said source of electrical energy for the duration of said predetermined time interval of said time delay switch.

13. The combination defined in claim 12, and means for periodically closing said additional switch at said predetermined instants of successive cycles of operation of the engine.

14. In a fuel injection arrangement for an internal combustion engine, in combination, an electrically operated valve means for controlling the flow of fuel to the internal combustion engine, said valve means when unenergized occupying its closed position and when energized occupying its open position; a source of electrical energy; a transistor having a base, an emitter and a collector, said emitter and collector being in circuit with said source of electrical energy and with said valve means; voltage supplying means operatively associated with the engine and in circuit with said base and emitter of said transistor for impressing thereacross, at a predetermined instant during a cycle of operation of the engine, a voltage greater than that which is required to render said transistor conductive; and a resistor-capacitor time delay circuit connected across said base and emitter of said transistor and adapted to be charged by said voltage supplying means, while the latter impresses a voltage across said base and emitter, to a voltage greater than said voltage which is required to render said transistor conductive, whereby said transistor remains conductive for a predetermined time interval following the cessation of the impression of voltage by said voltage supplying means.
